UNITED STATES PATENT OFFICE.

OLIVER C. DENNIS, OF WILMETTE, ILLINOIS.

ELECTRIC VULCANIZER.

1,301,233.

Specification of Letters Patent. Patented Apr. 22, 1919.

Application filed March 6, 1917. Serial No. 152,478.

To all whom it may concern:

Be it known that I, OLIVER C. DENNIS, a citizen of the United States, and a resident of Wilmette, in the county of Cook and 5 State of Illinois, have invented certain new and useful Improvements in Electric Vulcanizers, of which the following is a full, clear and exact description.

The invention relates to portable electric 10 vulcanizers. One object of the invention is to provide a vulcanizer of this type which is simple in construction and in which the connections between the flexible conductor cord and the vulcanizer are effectively protected 15 from breakage or being short circuited.

A further object of the invention is to 20 provide a vulcanizer of this type which is adapted to be applied to the work by an ordinary screw clamp and which is completely disconnectible from the clamp.

A further object of the invention is to 25 provide an improved portable electric vulcanizer which is simple in construction, efficient in operation and can be produced at a low cost.

In the drawings: Figure 1 is a section of 30 a vulcanizer embodying the invention. Fig. 2 is a section taken on line 2—2 of Fig. 1. Fig. 3 is a section taken on line 3—3.

The improved vulcanizer comprises a cup-shaped body having a concave bottom 5, and a cylindrical outer wall 6, the bottom being concave to receive a patch to be applied to a tire tube or other rubber article. The body 35 is made of sheet metal. An electric heating or resistance element consisting of a coil of suitable wire 7 wrapped around a strip of mica 8 and a disk 9 of mica between the heating element and the bottom 5 of the vulcanizer body, are disposed in the body.

Above the heating element is placed a disk 10 of asbestos to direct the heat downwardly toward the bottom 5 and a metallic disk 11 is placed on top of the asbestos disk 10. A 40 hollow conoidal cap 12 is secured on the top of the disk 11. Insulation 9, heating element 7, asbestos 10, disk 11 and the cap plate 12 are all secured and clamped together in the body by an inturned flange 14 on the side 6 of the body. In the manufacture of the vulcanizer after the parts 9, 7, 10 and 11 have been placed in the body, the flange 14 is bent inwardly and downwardly to hold all parts in the body in fixed and 50 clamped relation so that separate means for securing the parts in the vulcanizer against

displacement will be avoided. This manner of constructing the body and contained parts makes it possible to produce the vulcanizer at a low cost and prevents breakage 60 of said parts.

A pair of clamping members or blocks 15 and 16 of insulating material are secured on the top of disk 11 by screws 17 which pass through said plates and into said disk. 65 Said screws serve to clamp the plates 15 and 16 together and to secure them to disk 11. Terminals 18 and 19 of the heating element 7 are extended upwardly from said element through a central opening in disk 11 and as 70 bestos 10 and an opening 20 in clamping member 15. A bushing 21 of insulating material is disposed above the hole in disk 11 to prevent electrical contact between the terminals 18 and 19 and the metallic body 11. 75 Conductor wires 22 and 23 of a conductor cord 24 have their terminals extended between the clamping members 15 and 16 and the terminals 18 and 19 of the heating element are placed in contact with said conductors respectively and these terminals are clamped together in firm contact when the member 16 is clamped against member 15. The conductor cord 24 is extended through an opening 25 in one side of the cap 12, and 80 is provided with a suitable plug 26 for the connection to a socket of any suitable or usual construction and which is adapted to be connected to a battery. Cord 24 is extended through hole 25 which is at one side 85 of the cap and thence to the opposite side and connected to the clamp 15, 16, so that the cord will be looped in the cap to prevent a direct pull on the clamped conductor terminals, if a pull should be accidentally exerted upon the conductor cord. 90

In operation, the vulcanizer, in its entirety, may be placed on top of a patch and a tire tube or article to which the patch is to be vulcanized and held thereon by an ordinary screw clamp 30 shown in dotted lines in Fig. 1, which is completely disconnectible from the vulcanizer. If desired, a pocket 27 may be formed in the top of cap 12 to receive a centering pin or projection 28 on the 105 screw of the clamp to position the vulcanizer in the clamp.

The invention exemplifies a portable electric vulcanizer which is simple in construction and can be produced at a low cost. The 110 several parts are efficiently secured against displacement in the body by being clamped

therein without additional clamping means. The conductor terminals are secured to terminal blocks which are protected by the cap and short circuit of the terminals is efficiently prevented.

The invention is not to be understood as restricted to the details set forth, since these may be modified within the scope of the appended claims, without departing from the 10 spirit and scope of the invention.

Having thus described the invention, what I claim as new and desire to secure by Letters Patent, is:

1. In an electric vulcanizer, the combination of a body, a resistance element, insulation and a metallic disk, said element, insulation and disk being disposed in superposed relation and clamped in the body to secure the element, insulation and body 15 against relative displacement, an insulating clamp centrally disposed on said disk to which the terminal of the resistance element is connected, and conductors leading to said clamp.
2. In an electric vulcanizer, the combination of a body comprising a bottom and a side wall, a resistance element, insulation and a metallic disk, said element, insulation and disk being disposed in superposed relation in said body, the side-wall being bent inwardly to clamp the element, insulation and disk in the body to secure them against displacement, and conductors leading to said resistance element.
3. In an electric vulcanizer, the combination of a body comprising a bottom and a side wall, a resistance element, insulation and a metallic disk, a hollow cap, said cap, disk, element and insulation being 30 clamped in said body by said cap, and conductors for supplying potential to said resistance element, said cap being adapted to be engaged by a clamp to secure the work to the vulcanizer.
4. In an electric vulcanizer, the combination of a body comprising a bottom and a side wall, a resistance element, insulation and a metallic disk, a hollow cap, said cap, disk, element and insulation being clamped 40 in said body, an insulating clamp centrally disposed on the disk and within the hollow cap, and to which the terminals of said element are connected, and conductors for supplying potential connected to said clamp.

5. In a portable vulcanizer, the combination of a body, a resistance element, insulation, a disk secured in said body, a clamp comprising members of insulation secured to the top of said disk, a plurality of conductors having terminals held between said 55 clamp members, and a hollow cap provided with a centrally elevated surface adapted to be engaged by an exterior clamp to hold the body to the work and in which the clamp of insulation is disposed, the terminals of the resistance element being also secured between said clamp-members.

6. In a portable vulcanizer, the combination of a body, a resistance element, insulation, and a disk secured in said body, a 60 clamp of insulation secured to the top of said disk, said disk having a hole therein, an insulating bushing in said hole, said element having both terminals extended through said bushing and held in said clamp 70 and conductors having terminals held in said clamp.

7. In a portable vulcanizer, the combination of a body, a resistance element, insulation, and a disk secured in said body, a 75 clamp of insulation secured to the top of said disk, said disk having a hole therein, one member of the said clamp having a hole therein, an insulating bushing in said hole, said element having both terminals extended through said bushing and said hole 80 in the clamp-member and held in said clamp, and conductors having terminals held in said clamp.

8. In a portable vulcanizer, the combination of a body, a resistance element, insulation, and a disk secured in said body, a hollow conoidal cap secured to said body, a clamp of insulation secured to the said disk and centrally disposed within said cap, and conductors having terminals held in said 90 clamp, the terminals from the resistance element being also held in said clamp.

9. In a portable vulcanizer, the combination of a hollow body, a resistance element, 100 insulation and a disk secured in said body, a hollow cap secured to said body and having a recess formed in the top thereof to receive a clamp screw, a clamp of insulation secured to the disk within said cap, 105 and conductors having terminals held in said clamp.

OLIVER C. DENNIS.
